DESIGN FOR A PARTS BOX

Gerald C. Montague, Urbana, Ohio

Application June 24, 1946, Serial No. 130,969

Term of patent 14 years

(Cl. D58—13)

To all whom it may concern:

Be it known that I, Gerald C. Montague, a citizen of the United States and resident of Urbana, in the county of Champaign and State of Ohio, have invented a new, original, and ornamental Design for a Parts Box, of which the following is a specification, reference being had to the accompanying drawings, forming a part thereof.

In the drawings, Fig. 1 is a perspective view of a parts box showing my new design, both ends being of the same appearance; Fig. 2 is a top plan view thereof; and Fig. 3 is a side elevation, and; Fig. 4 is an end elevation.

I claim:

The ornamental design for a parts box, substantially as shown.

GERALD C. MONTAGUE.
